UNITED STATES PATENT OFFICE.

JOHN H. STUKE, OF BEARDSTOWN, ILLINOIS.

SAW-SET.

No. 858,835.

Specification of Letters Patent.

Patented July 2, 1907.

Application filed February 17, 1906. Serial No. 301,651.

To all whom it may concern:

Be it known that I, JOHN H. STUKE, a citizen of the United States, residing at Beardstown, in the county of Cass and State of Illinois, have invented certain new and useful Improvements in Saw-Sets, of which the following is a specification.

My invention pertains to improvements in what are known as saw-setting tools of the plier type. Its object is to provide for the requisite tooth-setting operation with facility and effectiveness and to carry out these ends in a simple and ready manner.

Said invention therefore consists of certain structural features substantially as hereinafter fully disclosed and specifically pointed out by the claims.

15 In the accompanying drawings illustrating the preferred embodiment of my invention—Figures 1 and 2 are opposite side elevations thereof. Fig. 3 is a sectional elevation of the same produced in the direction of the axis of the saw-blade clamping wedge or jaw. Fig. 20 4 is also a sectional elevation thereof at right-angles to the plane of the aforesaid section. Fig. 5 is a like section as Fig. 3, produced on a different line.

In carrying out my invention, I employ what may be called a stationary jaw-member 1 having an integral or 25 fixed arm or lever 1^a, and a lever or pivoted arm 1^b fulcrumed upon or in the heel-end of the aforesaid member, a preferably flat-metal spring 2 being interposed between said arms or levers and exerting or delivering its pressure or action upon the pivoted arm or lever one 30 end of said spring being suitably secured to the integral arm or lever.

A clamping wedge or jaw 3 is arranged within the jaw-member 1, the latter being provided for that purpose with an opening 1^c of a corresponding outline as that of the former and being a continuation or extension of a practically circular opening 1^c in said jaw-member, said openings both being accessible laterally through each side thereof, the purpose of which will presently appear. Said clamping wedge or jaw 3 has passing 40 therethrough, and is actuated as later described by a screw-threaded rod 4 also extending through, and guided by a corresponding passage 5 in the opposite end of the member 1, and terminated in a flat or plate-like portion 4^a provided with an angular or cam slot 4^b receiving a pin or stud 1^d projecting laterally from the upper end of the lever 1^b. Said flat or plate-like portion 4^a of the rod 4 works partially within a recess 1^e of the jaw-member 1 and is adapted to engage the end-wall thereof for controlling the movement of the rod 4 in one direction, said cam-slot equipped portion 4^a also being let into a recess 1^f in one end of the lever 1^b and guided in its movement and held against lateral displacement thereby, as it is actuated by the stud or pin 1^d in partaking of the movement imparted thereto by the angular or cam-slot 4^b receiving said stud or pin. Said clamping wedge or jaw 3 has its inclined surface presented

next to, and resting upon the correspondingly inclined or sloping surface of the laterally extended portion 1^a of the member 1 forming one wall of the opening 1^c and its opposite surface facing the other wall of said opening 60 1^c and which forms the face of the jaw-forming portion 1^g of said member, between which wedge and the latter is clamped and held the saw-blade in performing the tooth-setting operation. Also, said wedge 3 is capable of adjustment upon its carrying rod or connection 4 and 65 accordingly with relation to the face of the jaw-forming portion 1^g of the member 1 in accommodating the saw-blade, by means of an internally screw-threaded sleeve or tubular nut 6 threaded or working upon a screw-threaded surface of said rod and adapted to actuate or 70 move said wedge. To provide for effecting the latter, said sleeve or nut has at that end, opposite its headed end, an annular shoulder or enlargement 6^a let into, and adapted to turn in opposed horizontal slots 3^a formed in the lateral walls and at the inner end of a recess 3^b provided in the outer or larger end of said wedge for the reception bodily of said sleeve or nut. The headed end of the tubular nut or sleeve 6 is suitably milled or serrated for its effective manipulation.

A gage 7 for limiting or controlling the depth of insertion of the saw-blade between the jaw-forming portion 1^g and the wedge 3, and accordingly engaging, or constituting a stop for the end or top of the tooth to be set, is applied to the part 1^g, it being right-angled in general outline. One arm of said gage has a longitudinal slot 7^a and is equipped with a set or adjusting screw 7^b working through said slot, in a threaded socket or aperture formed in one side of said part 1^g of the member 1 for the requisite movement or adjustment of the gage. The other arm of the gage extends inward relatively beyond the face of the jaw or part 1^g and has a lateral extension or projection 7^c arranged to occupy a position opposite said jaw face, and for immediate engagement with, and to form a stop for the point or top of the saw-tooth. This arrangement provides, as 90 95 is obvious, for the uniform gaging of the saw-teeth throughout the blade and for accommodating, as before noted, various sizes of teeth in effecting the setting of the same.

An anvil or block 8 for the tooth, being set, having 100 an inclined or sloping surface or face for imparting the requisite set or deflection to the tooth, is suitably arranged in an opening 1^h in the jaw-portion 1^g of the member 1, it being pivoted as at 8^a therein so as to provide for the requisite movement of the anvil in varying 105 the set or deflection of the tooth. As contributory to that end a set or holding screw 8^b is arranged to work in a bridge piece or bearing 8^d suitably held in cleats 8^e integral with the jaw-forming part 1^g of the member 1, said screw also being adapted for forming an abutment 110 for the block or anvil 8 when in use, as will be readily understood.

A spring-cushioned and automatically retractable setting pin or plunger 9, diagonally arranged for movement within a corresponding passage 1ⁱ formed in the inner end of the member 1, has its inner end adapted 5 to engage the saw-tooth and the outer headed or enlarged end adapted to be engaged by an offset or lug 1^b integral with the lever 1^b and which lug or offset, by the suitable actuation of the latter, is effective to force inward said plunger and cause it to engage or act upon 10 the saw-tooth in performing the setting operation, as is apparent.

It is thought that the foregoing is clearly and fully suggestive of the use and operation of the invention, it being noted, however, that, with the saw-blade in position as aforesaid, and the grasping and actuating of 15 the lever 1^b, the saw-blade will be suitably gripped or clamped and held in position while the suitable setting of the tooth is successively effected, all thus being performed by a single or continuous operation and without 20 any subsequent or additional manipulation of parts.

I claim—

1. A saw-set of the plier-type, comprising a handled stationary jaw-member, an anvil, a plunger and a clamping wedge operatively arranged in said jaw-member, and said plunger opposed to said anvil, a lever pivoted in said jaw-member and effective to actuate said plunger, means of connection between said wedge or clamp and said lever, and a pin and cam-slot connection between said lever and the aforesaid connecting means. 25

2. A saw-set of the plier-type, comprising a handled stationary jaw-member, an anvil, a plunger and a clamping wedge operatively arranged in said jaw-member, and said plunger opposed to said anvil, a lever pivoted in said jaw-member and effective to actuate said plunger and equipped 30 with a lateral pin, and a rod adjustably connected to said wedge and having a plate-like terminal provided with a cam-slot engaged by said lateral pin of said lever. 35

In testimony whereof I have signed my name to this specification in the presence of two subscribing witnesses.

JOHN H. STUKE.
